UNITED STATES PATENT OFFICE.

EDWARD S. HUFF, OF MIAMI, FLORIDA.

AUTOMOBILE STARTER.

Application filed June 27, 1923. Serial No. 343,607.

My invention relates to automobile starters, and an object of my improvements is to lock the starter mechanism so that the motor shall not be inadvertently geared with the engine when the latter is in motion. Incidentally when the parts are adjusted to locking position the ignition circuit is broken.

In the accompanying drawings.—

Figure 1 is a partial diagrammatic 10 tail view embodying my invention and illustrating its connection with the engine and starting motor of an automobile, the front wall of the switch casing being removed to show the interior construction.

Fig. 2 is a section on the line II—II, Fig. 1.

Fig. 3 is a section on the line III—III, Fig. 1, the rollers d^4 being omitted.

Fig. 4 is a view of the switch case partly 20 broken away, with the cover of the vacuum chamber removed to show the diaphragm.

Fig. 5 is a section similar to Fig. 3 showing the parts in locked position.

Fig. 6 is a central vertical section of the 25 switch casing, the parts being shown in locked position.

Fig. 7 is a section on the line VII—VII, Fig. 1.

Fig. 8 is a view similar to Fig. 1, the parts 30 being shown in the position they occupy when the starting apparatus is operative when starting the engine.

a represents the starting motor. a^2 is a 35 movable gear wheel on the shaft of said motor. b represents the engine and b^2 a gear wheel connected with the engine and adapted to be engaged by the gear wheel a^2 to connect the motor to the engine for starting the latter. The energizing of the motor a throws 40 the gear wheel a^2 into mesh with the gear wheel b^2 in a way well understood, and therefore, not specifically described and illustrated.

c is the casing for the switch apparatus 45 for making and breaking the circuit through the motor a . c^2 is a cylindrical casing extending upward from the upper end wall of the casing c . c^3 is a similar cylindrical projection axially in line with c^2 but extending 50 downward from the lower wall of the casing c . d is a rectangular cross-head, its flat end faces bearing against the side walls of the casing c and its side walls engaging friction rollers d^4, d^4 so that said cross-head is guided 55 in its vertical reciprocation. f, f are the binding posts for the wires f^2, f^2 , which

communicate with the motor a and through which said motor is energized. d^2 is a contact strip secured to the lower end of the cross-head d and adapted to contact and complete the circuits between the binding 60 posts f, f when said cross-head is at the lower end of its travel. The cross-head d extends in a cylindrical portion into the projection c^3 and therein is surrounded by a helical 65 spring d^3 , which spring acts to force the cross-head d to the upper end of its travel. d^5 is a cylindrical rod fitting and adapted to reciprocate in a horizontal aperture extending inward from one of the end faces of the 70 cross-head d . d^6 is a light helical spring tending to force the end of the rod d^5 out of the aperture in the cross-head d . c^4 is a circular hole through a side wall of the casing c so located that it shall be axially in line 75 with the rod d^5 at an intermediate position of the cross-head d and of such a size that said rod may readily extend into said hole.

g is a corrugated diaphragm secured to one of the side walls of the casing c so that 80 its center is in line with the center of the hole c^4 . c^5 is a concavo-convex cover or securing plate, the periphery of which is adapted to engage over the diaphragm g at its edge. Said cover is bound in position by 85 screws and firmly secures the diaphragm g in position somewhat spaced from the wall of the casing c and affording a chamber c^6 outside of said diaphragm. g^2 is a cylindrical metal piece secured at the center of the 90 diaphragm g and adapted to extend into the hole c^4 and fill the same when the diaphragm g is in normal position, thus presenting a smooth unobstructed inner surface of the wall of the casing c upon which the cross-head d may reciprocate. The diaphragm g is of such elastic strength that it prevents 95 the rod d^5 from entering the hole c^4 under the impulse of the spring d^6 when said diaphragm is in its normal position.

b^3 is a pipe connecting the intake passage 100 b^3 of the engine with the vacuum chamber c^6 of the casing c .

e is a cylindrical rod pivotally connected to the upper end of the cross-head d and 105 provided with a laterally-extending lug e^2 . e^4, e^4 are eccentric lugs connected with the rod e to limit the angular motion of said rod relative to the cross-head d by engaging against the latter. e^{3a} is the cylinder of a 110 pin lock which may be operated by a key from the upper end to turn the rod e .

*c*⁸ (Figs. 7 and 8) is a narrow slot through the upper wall of the casing *c* and through the lower wall of the projection *c*². *e*³ is a pin extending laterally from the rod *e* and adapted to pass into the slot *c*⁸ to permit the full downward motion of the rod *e* with the cross-head *d* or to engage at another angular position as shown in Fig. 7 to prevent the full downward travel of said rod and cross-head.

h, *h* are binding posts upon the side of the casing *c*. *h*² is an elastic tongue which normally breaks the connection between the binding posts *h*, *h*. When the rod *e* is turned to the position shown in dotted lines in Fig. 2, the lug *e*² engages against the elastic tongue *h*² and completes the circuit between the binding posts *h*, *h*. The binding posts *h*, *h* are interpolated in the ignition circuit 20 of the engine.

The operation of the above described apparatus is as follows:

The apparatus is put in operative condition by a key, as shown in Fig. 8, turning the rod *e* to such angular position that the pin *e*³ shall be free to pass into the slot *c*⁸. Now if the engine is in motion a vacuum will be created in the intake passage *b*³ which will be communicated to the chamber *c*⁶ through the pipe *b*⁰ and flex the diaphragm *g* outward, removing the cylindrical block *g*² from the hole *c*⁴. Now should the operator inadvertently attempt to connect the motor *a* with the engine while the latter is running, he would press downward upon the rod *e*, pressing the cross-head *d* downward. When the rod *d*² came opposite the hole *c*⁴ the spring *d*⁶ would force said rod outward, engaging its end in said hole and locking the cross-head *d* in its intermediate position, indicated by broken lines in Fig. 1, in which the contact strip *d*² has not yet reached the binding posts *f*, *f* to complete the motor circuit. Thus the apparatus would not act to engage the teeth of the gear wheel *a*² with that of the gear wheel *b*² when the engine was in motion.

When the engine is at rest the vacuum will be released in the intake passage and chamber *c*⁶ and the diaphragm *g* will return to the position shown in Fig. 3, forcing the rod *d* out of the hole *c*⁴ and preventing its entering therein so that the operator is free to depress the rod *e* and cross-head *d* to complete the energizing circuit through the motor *a* and engage the gear wheels *a*² and *b*² to start the motor.

When the rod *e* is turned to the position indicated in Fig. 7, the pin *e*³ will engage above the upper wall of the casing *c* and the lower wall of the cylindrical projection *c*², as indicated in Fig. 7, and prevent the depression of the rod *e* and cross-head *d* to connect the energizing circuit of the motor. At this time, in the construction shown, the lug

*e*² is out of engagement with the contact strip *h*² and the ignition circuit is broken. Thus the operator in turning his key to release the same and to break the ignition circuit locks the starting switch so that the starting motor cannot be energized to start the engine.

What I claim is:

1. In an apparatus of the kind described, an engine, an electric motor for starting said engine, means whereby the starting of said motor shall engage the same with said engine for starting the same, an energizing circuit for said motor, a switch for making and breaking said circuit provided with a part adapted to be moved to lock said switch in its disengaged position, an ignition circuit a make-and-break apparatus for said ignition circuit, said part being adapted to cause said make-and-break apparatus to interrupt the ignition circuit when said part is moved to lock said switch in its disengaged position.

2. In an apparatus of the kind described, an engine, a starting motor therefor, means for engaging said motor and engine to start the latter, said means consisting in part of a reciprocating part, a latch adapted to automatically engage to prevent the motion of said reciprocating part, means for preventing the operation of said latch, and automatic means depending upon the operation of said engine for actuating said means for preventing the engagement of said latch to permit the engagement of the same.

3. In an apparatus of the kind described, an engine, a starting motor therefor, means for engaging said motor and engine to start the latter, said means consisting in part of a reciprocating part, a latch adapted to automatically engage to prevent the motion of said reciprocating part, means for preventing the operation of said latch, and means dependent upon the vacuum in the intake of the engine for actuating said means for preventing the engagement of said latch to permit the engagement of the same.

4. In an apparatus of the kind described, an engine, a starting motor therefor, means for engaging said motor and engine to start the latter, said engaging means consisting in part of a reciprocating cross-head, a spring-actuated latch on said cross-head adapted to engage to prevent the motion of the same when extending out of said cross-head, and means dependent upon the operation of the engine for preventing said latch from extending from said cross-head.

5. In an apparatus of the kind described, an engine, a starting motor therefor, means for engaging said motor and engine to start the latter, said engaging means consisting in part of a reciprocating cross-head, a spring-actuated latch on said cross-head adapted to engage to prevent the motion of

- the same when extending out of said cross-head, and actuated means for preventing said latch from extending from said cross-head.
- 5 6. In an apparatus of the kind described, an engine, a starting motor therefor, means for engaging said motor and engine to start the latter, said means consisting in part of a reciprocating cross head *d*, a latch on said 10 cross-head, a spring pressing said latch out of said cross-head so as to engage in an aperture to prevent the reciprocation of said cross-head, a diaphragm, a part on said diaphragm interposed in the line of motion of 15 said latch and adapted to prevent the same from being forced out of said cross-head, said diaphragm being within a chamber, said chamber being in communication with the intake of the engine.
- 20 7. In an apparatus of the kind described, an engine, a starting motor therefor, means for engaging said motor and engine to start the latter, said engaging means consisting in part of a reciprocating cross-head, a part 25 adapted to reciprocate to actuate said cross-head and to turn relative thereto, the last-
- named part being adapted to be locked in the disengaged position of said cross-head at one angular position and to permit the full reciprocation of said cross-head in a 30 different angular position.
8. In an apparatus of the kind described, an engine, a starting motor therefor, means for engaging said motor and engine to start the latter, said engaging means consisting 35 in part of a reciprocating cross-head, a part adapted to reciprocate to actuate said cross-head and to turn relative thereto, the last-named part being adapted to be locked in the disengaged position of said cross-head 40 at one angular position and to permit the full reciprocation of said cross-head in a different angular position, an ignition circuit, and means whereby said reciprocating and rotating part shall cause the making of 45 said ignition circuit at one angular position and the breaking of said circuit at another angular position.

In testimony whereof, I sign this specification,

EDWARD S. HUFF.
